UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

INKING MECHANISM

Original application filed May 26, 1926, Serial No. 111,787. Divided and this application filed April 6, 1929. Serial No. 353,198.

This is a division of my application for patent, Serial No. 111,787, filed May 26, 1926, on a high speed printing press.

in my prior Patent No. 1,584,828, May 18, 1926, with a magnetic brake on the end of the cylinder shaft.

Other objects and advantages of the invention will appear hereinafter. 55

Reference is to be had to the accompanying drawings in which

Fig. 1 is a side view, diagrammatic in part, showing the arrangement of the printing cylinders and various parts of a preferred 60 form of the inking mechanism;

Fig. 2 is a side view of a part of the inking mechanism on the left side of Fig. 1 showing the ink fountain in longitudinal section;

Fig. 3 is a fragmentary plan of the same; 65

Fig. 4 is a sectional view of the blade and its cooperating parts;

Fig. 5 is a rear view of one side of the ink fountain showing means for varying the speed of the fountain roll to control the supply of ink; 70

Fig. 6 is a sectional view on the line 6—6 of Fig. 5 on an enlarged scale;

Fig. 7 is a vertical central sectional view at the end of the fountain roll showing the 75 method of supporting it in the ink fountain;

Fig. 8 is a similar view of the bearing for the pick-up roll;

Fig. 9 is a sectional view of the bearing and magnetic brake for the ink cylinder shaft; 80

Fig. 10 is an end view of part of the inking apparatus on a large scale, showing the adjustment of the distributing roll relative to the pick-up roll and inking cylinder;

Fig. 11 is an end view of a detail, taken in the direction of the arrow 11 in Fig. 10, and

Fig. 12 is a side view, with parts in section, of the adjusting rod shown in Fig. 10.

Referring to the first sheet of drawings, I have shown one unit of this press connected up to be run by the main shaft S connected to a shaft section S⁴ by a clutch C. 90

I have shown diagrammatically the course of the web through the printing couples. On the main shaft section is a miter gear driving a vertical shaft 15 which is the driving shaft for the press unit. This shaft, through gearing 16, drives the printing couples. The two impression cylinders 17 are driven at the same rate in opposite directions and the plate 100

5 provide the usual adjusting keys for controlling the supply of ink to the different columns that are fully accessible to the operator, constructed so that the blade is brought against the fountain roller by pushing it in and is withdrawn by yielding means when released, and means for operating and adjusting these blades in a very simple manner and in a convenient place readily accessible; to provide means whereby the adjusting screws are arranged in proper alignment with the several columns or webs so that the operator can easily select the ones to be adjusted; to provide means whereby the speed of the fountain roller can be regulated readily to deliver ink, independently of the individual adjustment of the fountain keys and in such a way that the operator will not have to open every key on the device when he is changing from one kind of printing to another, as for example from ordinary newspaper work to half tone illustrations or letter press printing or vice versa; to provide an ink fountain which is absolutely protected against the possibility of ink leaking through; to provide the ink fountain in such a form that a plurality of kinds or grades of ink can be run in the press at the desired times without complicated and time-consuming changes; to provide a convenient means for adjusting the relation of the distributing roll with respect to the ink cylinder and also with respect to the pick-up roller without danger of these two adjustments interfering with each other, and so that each one can be made and set and will not be disturbed by the making of the other adjustment; to provide a simple and practicable means whereby the necessary variations of speed of the ink fountain roll for the purpose of controlling the amount of ink fed to the press can be obtained; to provide an extremely simple means for preventing the fountain roll from carrying paper dust and bits of paper back into the ink; and to provide a novel way of combining the eccentrically adjusted boxes and back-lash device as set forth

cylinders 18 are driven therefrom at the same speed so that the web passes through one couple and up over an adjustable roller 19 located above the printing couples and be-
5 tween them.

The plate cylinder 18 on each side is pro-
vided with a gear on the end which drives
the two form rolls 65 and there is gearing
also driving a gear 103 on the ink cylinder
10 shaft, the distributing rolls 67 and the gear
102 on the pick-up roll 68. The pick-up roll
is located directly over the fountain 70. In
this fountain is located the fountain roll 71
as is well understood in this art. The pick-
up roll has on its shaft a spiral gear 72 which
drives a complimentary gear 73 loose on a
vertical shaft 74. Also mounted loosely on
this shaft is a spur gear 75. These gears are
connected by speed change back gears 76 and
20 77 and double clutch 78. On account of a
difference in the speed ratios the shaft 74 can
be driven at two different rates of speed by
throwing the clutch in either direction. The
box containing the speed change gears 73, 76,
25 77 and 75 is closed by a guard or door 87.
The clutch is operated by a handle 79 on the
frame 14. On the bottom of this vertical
shaft 74 there is a bevel gear 86 which drives
the shaft of the ink fountain roll 71.

30 There are two methods of driving ink
fountain rolls, intermittently by a ratchet
and continuously. It is desired to be able
to increase or decrease the relative speed of
a fountain roll so as to increase or decrease
35 the amount of ink fed to the press. With
the ratchet motion this is done easily by alter-
ing the length of the throw and the ratchet
lever to take more or less teeth. Where a
fountain roll, however, is driven continu-
40 ously there has never been any method used
of changing its relative speed. This re-
quired the printer to increase or decrease his
ink by readjusting his fountain screws,
which was a tedious and uncertain method of
45 doing it, and it was because of this annoy-
ance that continuously driven fountain rolls
have not been used before. By my method
of employing change gears I am enabled to
effect the necessary variations of speed and
50 so have at last made practical the continu-
ously running fountain roll.

The lower spiral gear 73 acts as a worm
wheel receiving power from the worm 72 on
the end of the pick-up roller. When the
55 clutch is raised it delivers power to the ver-
tical shaft 74 at a higher speed so that no
change is necessary for a change of speed and
increase in the amount of ink, except to raise
or lower the clutch.

60 This change in speed of the fountain roller
is provided for the purpose of feeding more
or less ink regardless of the individual ad-
justment of the fountain keys so as to pro-
vide for printing half tones or illustrations
65 with this simple adjustment, for furnishing

additional ink without opening each key on
the fountain. This constitutes a method of
providing for this change in a much simpler
manner than has been used heretofore.

It will be noticed that the fountain roll is
driven in this way at one end by a vertical
shaft extending down from above instead
of the usual method of driving it by gearing
on the end of the fountain roll shaft and out-
side the fountain. The ink fountain is made
70 so that it cannot possibly permit ink to leak
through. It is made different from the ordi-
nary ink fountain by reason of the fact that
the shaft of the ink fountain roll does not
extend through the wall of the fountain and
75 thus furnish a source of leakage, present
even in the best machines heretofore. On
account of this shaft extending down, no
bearing has to be provided through the wall
80 of the fountain, but the bearing 80 is located
85 entirely within the fountain proper. The
ink fountain 70 is provided with the full bear-
ings 80 inside the fountain for supporting
the shaft of the fountain roll 71. This is
duplicated on the other side and a gear which
90 receives power from the pinion 86 is also
shown. On one side I have shown a guard
87^a, which of course is also duplicated on the
other side, for avoiding the splashing of ink
95 at the side. These guards are mounted on
brackets 88 on the frame 14 of the press unit.

The ink fountain is provided as usual with
a series of adjusting keys for the blade 90
100 for each column or other section of the page
so that the ink feed for such a column or
section can be adjusted at will. These keys
have to be made fully accessible to the oper-
ator. When the ink in a fountain feeds up-
wardly, as indicated in Fig. 1, the blade must
necessarily be placed within the confines of
the press where it is not readily accessible
ordinarily. I have provided certain novel
105 features by which the blade can be adjusted
from the front. I provide the flexible blade
90 with a series of pins 91 which obviously
can be pushed in to bring the blade against
the fountain roll at all points. I also provide
springs 91^a for pulling the pins out when the
pressure is released. These parts have to be
110 on the inner side of the inking device in the
press illustrated. These parts are mounted
on a frame 89 pivoted at 89^a so that they can
be turned back for cleaning the blade.

In order to operate the pins 91 from the
outer sides of the press units, I provide a series
115 of levers 92 each having a long arm and short
arm and pivoted on a cross shaft 93. The
short arms bear against the pins 91 indi-
vidually. Guide plates 94 are provided for
supporting the projecting ends of these pins.
The long arms of the levers 92 are substan-
tially horizontal and each one is supported
by an adjusting screw 95. These adjusting
screws extend upwardly from the pivot pins
96 by which they are connected with the arms
120 130

92. The adjusting screws are arranged in two rows, each set being carried at the top by a cross bar 97 through which the screws pass. The screws are arranged alternately as indicated in Fig. 3 so that each one can be readily reached by a pressman and operated. Each one is provided with a thumb nut 98 at the top for this purpose. These are accessible from the platform 2 through a trap door 99 located at the end of the ink fountain. This is lifted to expose the entire group of thumb nuts for adjusting purposes. It will be apparent that I maintain the advantages of having the fountain blades at the rear of the fountain and at the same time provide for their adjustment at the front, within easy reach of the operator. In this case, by front I mean the two exposed sides of the press unit.

In fountains of the same general type heretofore employed for this type of press, it has been necessary to bring all of the screws to one side of the press. This makes it necessary for the operator to find the particular screw which he may desire to operate for adjusting the ink on a certain column. On the contrary I have located the adjustments of the otherwise inaccessible fountain blade in alignment with the separate columns for webs. This makes it extremely easy on the part of the operator to find the proper screw which he needs for adjusting the ink on any particular column.

In the fountain I employ a scraper 6^a and screen 8^a. The cleaning blade 6^a works 35 against the ink fountain roll upon its returning side so as to prevent it from carrying into the ink paper dust and bits of paper which have been brought down to it by the inking rollers.

40 The pickup roll 68 is provided with a shaft 100 extending through it, mounted in ball bearings 101, carried on the frame 14 in stationary position. This pickup roll has the gear 102 by which it is driven by a train of 45 gears including the gear 103 on the shaft of the ink cylinder 66. The ink cylinder shaft 104 is also mounted in two sets of ball bearings 105 on the frame and another one on an outboard bearing 106. The gear 103 is located between the two bearings 105.

50 The shaft 104 is provided with a magnetic brake to bring the ink cylinder to a stop more quickly than has been possible heretofore. On the end of the shaft, and in fact of each 55 heavy revolving member, a disc 108 is provided fixed to a hub 109 keyed to the shaft. This cast iron disc revolves in close proximity to the field magnet 110 which is held stationary in the out-board bearing 106.

50 In Figs. 10, 11 and 12 the method of making certain adjustments in the inking mechanism is illustrated. In the frame 14 are two 65 projections 111 to which are bolted brackets 112. The distributing roll 67 is supported by bearings in sockets 115 carried adjustably

by socket holders 113 centered on the shaft 104. The distributing roll has to run in contact with the ink cylinder 66 and the pick-up roller 68 which are both mounted in stationary bearings. Two adjustments are provided for the distributing roller, one to adjust it radially with respect to the pick-up roll and the other radially with respect to the ink cylinder. These adjustments are designed so that they will not interfere with each other. In other words, when one adjustment is made, the changing of the other adjustment will not change the first one. The socket holder 113 is supported around the ink cylinder journal at one end and by 70 poppets and screws 114 carried by the brackets 112 at the other. The operation of these screws will cause the distributing roll to move in a circumferential direction relative to the ink cylinder so that it can move toward or 75 from the center of the pick-up roll.

The adjustment in the transverse direction is secured in the following way: The sockets 115 for supporting the distributing roll are tapped in at their ends and a screw 116 inserted in each one. These screws are held from longitudinal motion by two pins 117 fixed on the frame between two flanges 118 on the screw. The screw is rotated by a socket adjusting rod 119 provided with a 80 spiral gear 120 at its lower end meshing with a similar spiral gear 121 on the screw 116. The adjusting screw rod 119, as well as the screw 116, is provided with a square end and 85 pin hole by which it can be operated easily by the pressman. The rotation of this adjusting rod 119 turns the screw 116 and moves the socket 115 with the socket holder 113 radially with respect to the ink cylinder. 90 This adjustment does not interfere with the previous adjustment of the roller 67 into proper contact with the pick-up roll 68. The distributing rolls, or at least some of them, 95 are reciprocated as usual by crank shafts 123.

100 It will be seen from what has been said so far that the keys for controlling the supply of ink to the different columns are not only fully accessible to the operator on both sides of the press, but that the blade is brought 105 into contact with the fountain roller in a positive manner, operated from a convenient position and with the adjusting screws arranged in alignment with the several columns or webs to enable the pressman to select the right ones without trouble. Also the fountain roller can be speeded up very conveniently 110 to supply additional ink without opening up each key.

115 Furthermore, at least two grades of ink can be supplied and each one ready to be used 120 at any time without making any complicated changes. The ink fountain is fully protected against the possibility of any ink leaking through to the web at any point. Furthermore, the magnetic brakes are provided 125 130

for stopping the ink cylinder, at the same time as the press cylinders and thus bringing the press to a stop without the usual strains and danger of breaking the gears and also the web. The magnetic brake for one part of the device is combined in a novel way with the eccentrically constructed boxes and back lash device.

Although I have illustrated and described only a single form of the invention I am aware of the fact that modifications can be made therein by any person skilled in the art without departing from the scope of the invention as expressed in the claims. Therefore, I do not wish to be limited in this respect but what I claim is:—

1. In an inking mechanism for a printing press, the combination with an ink cylinder, distributing roll and pick-up roll, of a fountain located below the pick-up roll, a fountain roll, gearing for driving the ink cylinder, distributing roll and pick-up roll from the press, a shaft extending down from the pick-up roll to the fountain, means for driving the last named shaft from the pick-up roll, and a gear on the fountain roll driven by said shaft.

2. In an inking mechanism for a printing press, the combination with an ink cylinder, distributing roll and pick-up roll, of a fountain located below the pick-up roll, a fountain roll, gearing for driving the ink cylinder, distributing roll and pick-up roll from the press, a vertical shaft extending down from the pick-up roll to the fountain, means for driving said vertical shaft, said ink fountain having bearings inside the fountain for the fountain roll, and a gear on the fountain roll located inside the fountain, for driving the fountain roll from the pick-up roll through the vertical shaft, whereby the fountain does not have to be perforated for its shaft or bearing.

3. In an inking mechanism for a printing press, the combination with an ink cylinder, distributing roll and pick-up roll, of a fountain located below, a vertical shaft, means for driving said vertical shaft, said ink fountain having bearings inside the fountain for the fountain roll, and a gear on the fountain roll located inside the fountain, for driving the fountain roll through the vertical shaft, whereby the fountain does not have to be perforated for its shaft or bearing.

4. In an inking device for a printing press, the combination with the pick-up roll, ink distributing cylinders, and gearing for driving the pick-up roll from the other cylinders, said pick-up roll having a worm gear, a shaft having a gear thereon meshing with the worm gear for driving it and projecting down toward the top of the fountain, inside the end of the fountain, and a fountain roll in the fountain having its shaft located entirely within the fountain and having a gear there-

on arranged to be driven by the first named shaft.

5. In an inking device for a printing press, the combination with the pick-up roll, ink distributing roll, ink cylinder, and circumferential gearing for driving the pick-up roll from the other cylinders, said pick-up roll having a worm gear on its shaft, a vertical shaft having a gear thereon meshing with the worm gear for driving it and projecting down toward the top of the fountain inside the end of the fountain, a fountain roll in the fountain having its shaft located entirely within the fountain and having a gear thereon arranged to be driven by said vertical shaft, a second gear on the vertical shaft, a clutch by which either of said gears can be connected to it for driving it, a back shaft having gears thereon of different sizes meshing with the gears on the vertical shaft constantly, whereby the vertical shaft can be driven at different speeds to deliver more or less ink from the fountain roll.

6. In an inking mechanism for a printing press, the combination with an ink fountain, bearings located entirely within the fountain, a fountain roll supported by said bearings, and means above said bearings for rotating said fountain roll.

7. In an inking mechanism for a printing press, the combination with an ink fountain, bearings located within the fountain, a fountain roll supported by said bearings, and means for rotating said fountain roll.

8. In an inking device for a printing press, the combination with a fountain and fountain roll, of a blade extending across the fountain roll, a series of pins engaging the blade for pressing it against the roll, yielding means for drawing the pins back, a separate lever for operating each of said pins to press the blade against the roll, and means located at the outer side of the inking mechanism for individually adjusting and operating said levers.

9. In an inking device for a printing press, the combination with a fountain and fountain roll, of a blade extending across the fountain roll, a series of pins engaging the blade for pressing it against the roll, yielding means for drawing the pins back, a separate lever for engaging each of said pins for forcing it forward to apply pressure to the blade, and means located at the outer side of the inking mechanism for individually adjusting and operating said levers, said means comprising a series of bell crank levers having their pivots in alignment at the side of the ink fountain on which the blade is located and below it and a long arm extending all the way under the ink fountain to the opposite side.

10. In an inking device for a printing press, the combination with a fountain and fountain roll, of a blade extending across the

fountain roll, a series of pins engaging the blade for pressing it against the roll, yielding means for drawing the pins back, a separate lever for engaging each of said pins
 5 for forcing it forward to apply pressure to the blade, and means located at the outer side of the inking mechanism for individually adjusting and operating said levers.

11. In an inking device for a printing press, the combination with a fountain and fountain roll, of a blade extending across the fountain roll, a series of pins engaging the blade for pressing it against the roll, yielding means for drawing the pins back, a separate lever for engaging each of said pins for forcing it forward to apply pressure to the blade, a pair of bars extending across the ink fountain on the opposite side, said bars being perforated and having rods extending
 15 downwardly and connected with said levers for operating them individually, said rods being staggered to permit the operator to select the proper column for adjustment.

12. In an ink fountain, the combination with a fountain proper and a platform extending along the same on the accessible side having a trap door therein adjacent to the fountain by which the parts are made accessible, of a series of adjusting devices located
 25 under the trap door, a series of levers connected with said adjusting devices extending backwardly under the fountain to the opposite side, a blade on the opposite side, and means connected with said adjusting devices
 30 for positively applying pressure on the blade at points along the length thereof.

13. In an inking device for a printing press, the combination with an ink cylinder, of a pair of bearings therefor and an outboard bearing beyond one of them, means between the outboard bearing and the adjacent bearing for driving the cylinder, and a magnetic brake located in the space between the outboard bearing and the nearest of the
 45 first two bearings for stopping the ink cylinder when the motor stops, independently of the rest of the printing machine.

14. In an inking mechanism, the combination with an ink fountain roll and a pick-up roll having a shaft, of a spiral gear on the pick-up roll shaft, a shaft, a loose gear on the second shaft meshing with the spiral gear, a spur gear loose on the second shaft, a spur gear and a spiral gear rotatable together and meshing with the second loose gear and with the first named gear respectively, constituting back gearing, a clutch for connecting either of the loose gears to the shaft on which they run, and means for running the ink fountain roll from the second shaft.

In testimony whereof I have hereunto affixed my signature.
